[57] CLAIM

The ornamental design for a reflector for a warning light, substantially as shown and described.

DESCRIPTION

FIG. 1 is a top view of a reflector for a warning light in accordance with my novel design;

FIG. 2 is a bottom view thereof;

FIG. 3 is a front elevational view thereof;

FIG. 4 is a side elevation view taken from the left end of the reflector as shown in FIG. 3;

FIG. 5 is an elevational view thereof taken from the opposite end when compared to FIG. 3;

FIG. 6 is a side elevation view thereof taken from the opposite side when compared to FIG. 4; and

FIG. 7 is a front perspective view thereof.
